CLAIM

The ornamental design for a children's toy, substantially as shown and described.

DESCRIPTION

FIG. 1 is a top perspective view of a children's toy, showing my new design;

FIG. 2 is a front view of the children's toy of FIG. 1;

FIG. 3 is a rear view of the children's toy of FIG. 1;

FIG. 4 is a right side view of the children's toy of FIG. 1;

FIG. 5 is a left side view of the children's toy of FIG. 1;

FIG. 6 is a top view of the children's toy of FIG. 1; and,

FIG. 7 is a bottom view of the children's toy of FIG. 1.

The broken lines in the drawings are for the purpose of illustrating portions of the children's toy, which form no part of the claimed design.
